CLAIM

I claim the ornamental design for a sliding guard structure, as shown and described.

DESCRIPTION

FIG. 1 is a front perspective view of a sliding guard structure of the present invention, with doors in a closed position, and an optional electrical panel box shown in broken lines;

FIG. 2 is a front perspective view of a sliding guard structure of the present invention, with one door in an open position, and an optional electrical panel box shown in broken lines;

FIG. 3 is a front side view of a sliding guard structure of the present invention, with doors in a closed position;

FIG. 4 is a rear side view of a sliding guard structure of the present invention, with doors in a closed position;

FIG. 5 is a first side view of a sliding guard structure of the present invention, with doors in a closed position;

FIG. 6 is a second side view of a sliding guard structure of the present invention, with doors in a closed position; and,

FIG. 7 is a top view of a sliding guard structure of the present invention, with doors in a closed position.

The broken lines in the drawings depict unclaimed environmental subject matter.
